UNITED STATES PATENT OFFICE

WERNER UEBERMUTH, OF BERLIN-OBERSCHONEWEIDE, GERMANY, ASSIGNOR TO
GENERAL ELECTRIC COMPANY, A CORPORATION OF NEW YORK

ELECTRIC CIRCUIT BREAKER

Application filed February 17, 1932, Serial No. 593,621, and in Germany February 24, 1931.

My invention relates to electric circuit breakers, more particularly to high tension switches of the fluid-break type employing a pressure-confining chamber or explosion 5 pot within which arcing is extinguished.

The use of a conducting liquid, as water for example, as an arc extinguishing medium in high tension circuit breakers has been proposed. The type of circuit breaker 10 in this case generally involves a container for the conducting liquid at the bottom of which a stationary contact is positioned, and a movable rod contact which is withdrawn upwardly from the liquid into an air space 15 during the circuit interrupting operation. Since the switch contacts in the open circuit position are therefore further separated by an air space the circuit breaker structure when vertically arranged may be of considerable overall height.

The object of my invention is the provision of an improved high tension circuit breaker of the aforesaid type which shall be simple, compact and rugged in construction.

My invention will be more fully set forth in the following description referring to the accompanying drawing, and the features of novelty which characterize my invention will 30 be pointed out with particularity in the claims annexed to and forming a part of this specification.

Referring to the drawing, Fig. 1 is an elevational view, partly in section, of a high 35 tension circuit breaker embodying my invention and Fig. 2 is a view, partly in section, of structure shown in Fig. 1.

The fluid-break circuit interrupter shown by way of example comprises a so-called explosion pot 1 in the lower part of which is positioned a stationary socket contact structure 2 arranged to be engaged by the movable contact rod 3 in vertical alinement therewith. The explosion pot 1, comprising 45 a pressure resisting metal casing open at its upper portion to receive the rod contact 3, is partly filled with an arc extinguishing liquid 4, as water, so that the rod contact 3 may move out of the arc extinguishing liquid after interruption of arcing.

For the purpose of rigidly mounting the explosion pot there are provided lateral supporting pillars 5 and 6 positioned at opposite sides of the explosion pot and extending parallel to the longitudinal axis thereof. The pillars are mounted on suitable base structure, as the base member 7, which may be made portable, if desired, as by the rollers 8. The supporting pillars 5 and 6 comprise respectively the base insulators 55 9 and 10 on which are mounted the intermediate metallic supporting members 11 and 12. These members are provided with integral lateral supporting brackets 13 and 14, respectively, suitably joined, as by a 60 flanged connection, to corresponding brackets 15 and 16 joined to the metallic explosion pot 1. The upper portions of the pillars comprise the insulators 17 and 18 which support an arc shaped housing structure 19 65 70 in which the movable rod contact 3 is guided for vertical reciprocal movement.

The operating mechanisms for the rod contact 3 may comprise the usual straight-line linkage 20 connected to the lever 21 75 and rod 22. The pillar 5 is in the present instance hollow so as axially to receive the rod 22. The linkage 20 is pivoted to the structure 19, as at 23, and is pivotally connected to the lever 21 and to the rod 3 at 80 the points 24 and 25 respectively so that rotation of the lever 21 produces substantially straight line vertical movement of the rod 3. The actuating means may comprise a main shaft 26 mounted in the base member 7 connected, as by bellcrank 27, to the operating rod 22 and to a strong opening spring generally indicated at 28. The opening spring may be charged during closing 85 of the switch so as to be released in a well known manner causing high speed opening 90 of the switch.

The switch terminals in the present instance comprise the terminal lug 29, which is electrically connected by way of the metallic brackets and explosion pot to the stationary contact 2, and the conductor stud 30 which is suitably connected to the movable rod 3, as by a flexible lead (not shown). It will of course be understood that a poly- 100

phase arrangement may comprise the above described single phase units mounted on a single base structure.

Referring more particularly to Fig. 2, the explosion pot 1 is provided with an insulating lining 31 and an insulating baffle 32 provided with a centrally disposed aperture in alignment with the rod contact 3. As is well known, the arc formed upon initial separation of the contacts generates pressure within the surrounding liquid causing expulsion of liquid upwardly through the aperture in the baffle and interrupting the arc.

For the purpose of compensating loss of liquid due to evaporation, etc., there is provided a reserve reservoir 33 containing additional liquid connected to the explosion pot by a pipe 34, the outlet of which is positioned slightly below the normal level of the liquid within the explosion pot. The reserve reservoir may conveniently be disposed within the intermediate supporting member 12 as illustrated in Fig. 1. Lowering of the liquid level within the explosion pot so as to uncover the outlet of the pipe 34 admits air to the reservoir 33 so that liquid flows therefrom into the explosion pot until the normal level is restored. If desired, a liquid level gauge 35 may be connected to the pipe 34 so that the liquid level within the explosion pot may be known at all times.

Since the operation of this type of switch often involves vibration of the structure due to the sudden generation of high pressures, the above described arrangement is particularly advantageous as the supporting pillars including the insulators extending approximately parallel to the axis of the explosion pot are not subjected to bending stresses. Ceramic insulating materials may therefore be used without danger. For this reason switches of the above type may be readily employed for outdoor installations.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. A circuit interrupter of the fluid-break type comprising supporting pillars, an explosion pot containing an arc extinguishing liquid mounted between and laterally supported by said pillars, an operating linkage supported by said pillars, a contact rod operatively connected to said linkage guided for vertical movement so as to descend into said explosion pot, and base structure including an actuating shaft and an opening spring operatively connected to said linkage by a rod extending vertically through one of said pillars.

2. A circuit interrupter of the fluid-break type comprising a movable base member provided with rollers, a pair of insulating pillars mounted on said base member, an explosion pot disposed between and supported by said pillars, a housing mounted on the upper portions of said pillars, a contact rod guided within said housing and vertically movable to coact with said explosion pot, operating mechanism for said contact rod comprising an opening spring mounted on said base member, an actuating rod operatively connected to said spring and vertically movable within and axially of one of said pillars, and a linkage interconnecting said actuating rod and contact rod mounted within said housing.

3. A circuit interrupter of the fluid-break type comprising a base member, a pair of insulating pillars mounted on said member, each pillar comprising an upper insulator, a lower insulator and an intermediate metallic supporting member, one of said metallic supporting members forming a switch terminal, a metallic explosion pot containing an arc extinguishing liquid connected to and supported between said intermediate members, a contact rod vertically movable between said pillars so as to coact with said explosion pot, operating mechanism for said contact rod including a rod movable within and axially of one of said pillars, and a liquid reservoir for said explosion pot mounted on the other pillar and disposed within the intermediate member.

In witness whereof, I have hereunto set my hand.

WERNER UEBERMUTH.
